ERASER CLEANER

Emory W. Lewis, R.F.D. 1, Milan, Ohio

Filed Oct. 8, 1962, Ser. No. 72,023

Term of patent 14 years

(Cl. D9—2)

Fig. 1.

Fig. 2.

Fig. 3.

Fig. 4.

FIG. 1 is a perspective view of an eraser cleaner, showing my design;

FIG. 2 is a vertical sectional view taken through the center thereof;

FIG. 3 is a bottom plan view thereof; and

FIG. 4 is a back elevational view thereof.

The side not shown is substantially like the side shown.
I claim:

The ornamental design for an eraser cleaner, as shown and described.
